LINE-SPACING MECHANISM.

1,089,465.

Specification of Letters Patent. Patented Mar. 10, 1914.

Application filed May 24, 1911. Serial No. 629,138.

To all whom it may concern:

Be it known that I, HARRY A. FOOTHORAP, a citizen of the United States, residing at Harrisburg, in the county of Dauphin and State of Pennsylvania, have invented certain new and useful Improvements in Line-Spacing Mechanism, of which the following is a specification.

This invention relates to an improvement 10 in line spacing mechanism for typewriting machines and has for its object to produce a simple and efficient line spacing mechanism, which may be manufactured at small cost and readily assembled, and which may 15 be quickly set for any desired width of spacing.

A subordinate object of the invention is to simplify the structure by mounting both the line space rocker and the stop from the 20 platen spindle, so that the single screw, which ordinarily holds the thumb wheel in place, will serve to retain the entire assemblage of line space parts, with the exception of the adjusting screw for the stop.

25 In the accompanying drawings: Figure 1 is an end elevation of the platen carriage of a well known typewriting machine with the platen and my improved line spacing mechanism assembled thereon, the parts being in 30 normal position. Fig. 2 is a similar view with the parts in the positions they assume at the end of the line space movement. The stop in Fig. 2 is shown adjusted to a slightly 35 different position from that occupied by it in Fig. 1. Fig. 3 is a section on the line 3—3 of Fig. 1, with some parts broken away and others in elevation. Fig. 4 is a section on the line 4—4 of Fig. 1. Fig. 5 is a detail group of disassembled elements. Fig. 40 6 is a detail elevation of the line space wheel, and Fig. 7 is a detail view of the retaining device for the rocker retracting spring.

45 1 indicates the carriage of a typewriter in the end walls 2 of which the spindle 3 of the cylindrical platen 4 is afforded bearings. Beyond the outside of one of the end walls 2, the spindle 3 is formed with a reduced portion 5, which defines a shoulder 6, and 50 with a still further reduced extremity 7 which defines a second shoulder 8. At diametrically opposite points, the reduced part of the spindle, immediately adjacent to the shoulder 8, is cut away or flattened, as indicated at 9. The extremity of the spindle 3

is internally threaded for the reception of a head retaining screw 10, which holds in place the line space wheel 11, having a roughened knurled or toothed periphery 12 and a hub 13, upon which is secured, in any 60 approved manner, a rubber or other suitable thumb wheel 14, by means of which the platen 4 may be freely rotated, as is well understood in the art. The line space wheel 11 is formed in its inner face with a cavity 15 which receives the reduced extremity 7 and the squared or flattened end of the reduced portion 5 of the spindle and conforms to said flattened portion to prevent the wheel 65 from turning on the spindle or, stated otherwise, to compel the platen spindle and line-space wheel to rotate in unison. 70

Between the inner face of the line-space wheel and the shoulder 6 of the platen spindle, the line-space rocker 16 and the line-space stop member 17 are rotatably mounted 75 on the reduced portion 5 of the spindle, a washer 18 being preferably interposed between the rocker 16 and the adjacent end wall 2 of the carriage. Fulcrumed adjacent 80 to the outer end of the rocker 16, and spaced therefrom by a washer 19, is a line-space lever 20 formed at its outer end with a thumb piece 21, and at its inner end with a beak 22 and a check lug 23. Normally the check 85 lug 23 of the line-space lever 20 rests against the periphery of the line-space wheel 11 and limits the disengaging movement of the line-space lever but retains the beak 22 adjacent to, though disengaged from, the periphery 90 of the line-space wheel. When the finger piece 21 of the line-space lever is moved back, the rocking of the lever on its axis engages the beak 22 with the line-space wheel, and the wheel, line-space lever and line-space rocker 16 all oscillate in unison to effect the line-space movement of the platen. 95 This line-space movement of the parts is limited by the engagement of a stop projection 24 on the rocker 16, with the line-space stop 25 projecting from the stop member 17 and deflected laterally into the path of the projection 24 on the rocker, as clearly shown in Figs. 2 and 3.

In a mechanism of this character which 105 contemplates the employment of a single line-space stop, it is desirable to make provision for a comparatively wide range of adjustment of said stop to accommodate various widths of spacing. I therefore extend 110

rearwardly from the stop member 17 an arm 26, at the end of which is swiveled a nut 27 engaged by a stop adjusting screw 28, having a knurled head 29, a flange 30 and an intermediate unthreaded portion or neck 31, received within the plain bore of a stud 32, screwed into the end wall 2 of the carriage, as shown in Fig. 4. By rotating the screw 28 through the manipulation of its head 29, the nut 27 is caused to travel longitudinally of the screw 28, carrying with it the arm 26 of the stop member 17 and oscillating said member about the platen spindle as an axis, to adjust the position of the line-space stop 25. Obviously, by the adjustment of the line-space stop in the manner specified, the throw of the line-space rocker 16 and the consequent line-space movement of the platen 4 may be varied to secure any desired width of spacing within comparatively wide limits. Accidental rotation of the adjusting screw 28 and consequent disturbance of the predetermined position of the stop 20 25 is prevented by a binding screw 33, screwed into the stud 32 and bearing upon the neck of the adjusting screw.

To provide for the retraction of the line-space rocker and the line-space lever carried thereby, said rocker is provided with a radial arm 34 to which is attached one end 30 of a spring 35, whose opposite end is secured to a spring retaining member 36, secured to the wall 2 by a screw 37 and having a laterally deflected arm 38 which extends 35 under the lower edge of the wall 2. The spring 35 obviously tends to retract the parts when they are released after a line space movement and such retraction is limited by a stop pin 39 projecting from the wall 2 in 40 the path of the arm 34.

It will be observed that I have produced a simple and efficient line spacing mechanism, capable of universal adjustment, and that practically the entire mechanism is supported from the spindle of the platen and retained in place by a single screw. The spindle constitutes a single axial support for both the line-space rocker and the stop member, as well as the line-space wheel, all of 45 which parts are retained in their proper relative positions by the screw 10, which secures a line space wheel to the spindle.

It is thought that from the foregoing, the construction, arrangement, mode of operation and advantages of the illustrated mechanism will be clearly understood, but while the present embodiment of the invention is thought at this time to be preferable, I wish to expressly reserve the right to make such 55 changes, modifications, and variations of the illustrated structure, as may come fairly within the scope of the protection prayed.

What I claim is:

1. The combination with a platen and its 65 spindle, of an oscillatory line spacing device

and a coacting stop member, both mounted on the spindle, and an adjusting screw mounted to swing laterally from a relatively fixed part and operative to swing the stop member about the axis of the spindle to different positions of adjustment. 70

2. The combination with a platen and its spindle, of an oscillatory line spacing device and a coacting stop member, both mounted on the platen spindle to swing about the same as an axis, a relatively fixed part, an adjusting screw having a swiveled mounting on said fixed part to permit said screw to swing about a transverse axis, and a swiveled nut carried by the stop member and engaged by the screw. 75 80

3. The combination with a platen and its spindle, said spindle being reduced to form a shoulder, of a line space wheel secured to the end of the spindle, a line space rocker and a coacting stop member, both mounted on the spindle between said shoulder and the line space wheel, and a line space lever mounted on the rocker to engage the line space wheel. 85 90

4. The combination with a platen and its spindle, said spindle being reduced to form a shoulder, of a line space wheel secured to the end of the spindle, a line space rocker and a coacting stop member, both mounted on the spindle between said shoulder and the line space wheel, a line space lever mounted on the rocker to engage the line space wheel, and an adjusting screw operative to swing the stop member about the spindle to different positions of adjustment. 95 100

5. The combination with a platen and its spindle, the latter being formed with a shoulder, of a line space wheel, a screw retaining said line space wheel on the end of the spindle, a line space rocker and a coacting stop member, both loosely mounted on the spindle between said shoulder and the line space wheel, and a line space lever carried by the rocker and arranged to engage 105 the line space wheel. 110

6. The combination with a platen and its shouldered spindle, of a line space wheel, a screw retaining the line space wheel on the end of the spindle, a thumb wheel carried 115 by the line space wheel, a line space rocker and a coacting stop member, both swung from the spindle between the shoulder thereof and the line space wheel, and a line space lever mounted on the rocker to engage the 120 line space wheel. 125

7. The combination with a platen and its shouldered spindle, of a line space wheel, a screw retaining the line space wheel on the end of the spindle, a thumb wheel carried by 125 the line space wheel, a line space rocker and a coacting stop member, both swung from the spindle between the shoulder thereof and the line space wheel, a line space lever mounted on the rocker to engage the line 130

space wheel, and an adjusting screw for the stop member.

8. The combination with a platen and its spindle, said spindle being reduced to form 5 a shoulder, of a line space wheel secured to the end of the spindle, a line space rocker and a coacting stop member, both mounted on the spindle between said shoulder and the line space wheel, a line space lever mounted 10 on the rocker to engage the line space wheel, and means operative to swing the stop member about the spindle to different positions of adjustment.

9. The combination with a platen and its 15 spindle, of a line space rocker and a coact-

ing stop member, both swung from the spindle, a line space wheel, a screw retaining the line space wheel on the spindle and serving through the medium of the line space wheel to confine the rocker and stop member, a line space lever mounted on the rocker to engage the line space wheel and an adjusting screw for the stop member.

In testimony whereof I affix my signature in presence of two witnesses.

HARRY A. FOOTHORAP.
